Inventor

John Meyer
By his attorney, Atty

UNITED STATES PATENT OFFICE.

JOHN MEYER, OF COVINGTON, KENTUCKY.

VENT-BUNG.

SPECIFICATION forming part of Letters Patent No. 349,354, dated September 21, 1886.

Application filed December 14, 1885. Serial No. 185,558. (No model.)

To all whom it may concern:

Be it known that I, JOHN MEYER, a citizen of the United States, and a resident of Covington, in the county of Kenton and State of Kentucky, have invented a certain new and useful Improvement in Vent Bungs and Bushings, of which the following is a specification.

My invention relates to bungs for casks. Its object is to provide a convenient means for venting the cask.

With this object in view my invention consists in a hollow bung having a valved opening through its wall and the central opening closed by a globe, which is compressed within the opening to form an air-tight joint, the device so made forming a vent-bung.

It also consists in certain novel features and combination of parts which relate to the economic construction and effective working of the device, all of which will be first fully described in connection with the accompanying drawings and particularly referred to, and pointed out in the claims.

In the drawings, in which like parts are represented by similar reference-letters wherever they occur, Figure 1 is a vertical section of a bung and bush embodying my invention, showing the stopper in the sectional figure in dotted line and in full elevation above it. Fig. 2 is a detail view of the parts, the bushing and hollow bung being shown in vertical section and the globe or stopper in elevation above it. In this view the hollow bung is made in two parts diametrically divided instead of in one piece, as shown in Fig. 1. Figs. 3 and 4 are diametrical sections of modifications of the bung shown in Figs. 1 and 2. Fig. 5 is a similar sectional view of my device adapted to close the faucet-opening.

A is a metal bushing for the bung-hole, screw-threaded externally to be driven into the opening in the cask by a key or wrench applied to the key-seats *a*. It is also internally threaded to receive a hollow bung, B, which is externally threaded to engage the screw-threads in the bushing A. The interior of the part B is turned or cored out, forming an annular concave depression to form a seat for the globe stopper C, which is made of rubber or some elastic material. The part B has also key-seats *b* to receive the prongs of a key, by which

it is firmly screwed into the part A. The part B has a vertical perforation, *b'*, the lower portion of which is counterbored and screw-threaded to receive a short tube, *b*², the opening in which registers with the bore *b'*. The lower end of the tube *b*² has a thin strip of rubber, *b*³, secured around it and covering the lower end of the tube, this acts as a valve to admit air into the cask when the pressure within it is less than the atmospheric pressure and to prevent the flow of gases or liquids in the opposite direction.

The operation of the device so far as described, and as represented in Fig. 1, is as follows: The bushing A is intended to be permanently secured in the cask. The hollow bung B is screwed into the bushing A, after which the rubber globe C is forced into the bung B, where it will be retained in place by the annular depression. After the cask is emptied and is to be refilled the bung B is withdrawn, the cask is washed and refilled, and the bung B is screwed back to its place. It is obvious that the vent-bore *b'* and its valve at the bottom may be put through the bushing A, as shown in Figs. 3 and 4; but in the case of Fig. 3 it would be necessary to give the bung or bushing B a partial turn to elevate its flange a little above the bung-bush A to admit air for the proper ventilating of the cask, as shown in Fig. 3. In the form of bushing and hollow bung shown in Fig. 1 it is preferable to make both the parts A and B of metal and to have them united by a screw-thread, as shown. In the form shown in Fig. 2 the part B' is identical in construction with the part B, Fig. 1, except that it is diametrically divided. In the form shown in Fig. 4 the part A is left plain on the inside, as the ordinary faucet-bushings are now made. The two-part hollow bung B' may be made of wood, plain upon the outside and driven into the bushing, as the common bungs now are, after the globe C has been placed between the two parts, and in this case the globe may be made of glass or some inelastic material, which would firmly seat itself in the softer wood as the part B' is driven home. In case the bung B' be made of wood and the globe C of glass or inelastic material the vent-bore *b'* and tube *b*² should be in the bushing A. Otherwise the bore *b'* would be closed by compres-

sion when the bung is driven into its bushing. The bungs, as above described, are intended to be used as vent-bungs.

In Fig. 5 I have shown my bung constructed to be used as a faucet-bung. The only differences between the hollow bung B in this figure and the bung B in Fig. 1 are that when used as a faucet-bung the vent-perforation b' , tube b^2 , and its valve are omitted and the interior of bung above and below the annular depression which furnishes the seat for the elastic globe C tapers to fit the tapered shanks of the ordinary faucets. I intend this form to be used in combination with my vent-bungs before described in the same cask or barrel.

In use the globe C will be forced into its seat in the faucet-bushing B, and when it is desired to tap the cask the globe C is driven into the cask by the end of the faucet, as the common cork now is. After the cask is emptied the vent-bung B or B' can be removed to wash the cask. Then the globe C is removed from the barrel through the bushing.

When B and C are in use together, they constitute a bung. When the bung is used at the faucet-opening, and C has been driven inwardly out of the bung into the barrel by the faucet-

shank which is seated in B in the place of C, then B becomes a bushing for the faucet.

The faucet-bung illustrated in Fig. 5 is not claimed herein, as I intend to make the same the subject of a separate application.

What I claim as new, and desire to secure by Letters Patent, is—

1. The hollow bung, the valved opening extending through the same, and the stopper C, compressed within the bung, for the purpose specified.

2. The bung B, having vertical perforation b' , the tube b^2 , the opening of which forms the continuation of the said perforation, in combination with the spherical stopper C, substantially as set forth.

3. The combination, substantially as specified, of the bushing A, screw-threaded externally and internally, the bung B, having a valve-opening vertically through it and threaded externally to fit into the bushing A, with the spherical elastic stopper C to close the opening in the bung, substantially as described.

JOHN MEYER.
